Design No. 12,209, dated March 29, 1881.

UNITED STATES PATENT OFFICE.

CHARLES CHAMBELLAN, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,209, dated March 29, 1881.

Application filed February 16, 1881. Term of patent 3½ years.

To all whom it may concern:

Be it known that I, CHARLES CHAMBELLAN, of the city of New York, county of New York, and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

15 H is a group, consisting of the figure n, composed of fern-like sprays and of an open flower drooping on its stalk; also, of the figure a, a branching stalk bearing buds, and projecting from the figure d, and dividing into 20 sprays near its end; also, of the figure d, composed of circular daisy-like flowers, with a larger open rose-like flower on either side of the figure and accompanying leaves, and forming the center of the group; also, of the curving ornamented figure C.

B is a figure, composed of flowers resembling pinks, with accompanying leaves.

E is a figure made up of sprays of leaves and flowers.

30 K and J are bouquet-like figures of leaves and flowers, and O is a small leafy spray.

The groups and figures above described are set upon a regular patterned background.

I claim—

1. The design for carpets, consisting of the figure n, substantially as shown.
2. The design for carpets, consisting of the figure d, substantially as shown.
3. The design for carpets, consisting of the figure C, substantially as shown.
4. The design for carpets, consisting of the group H, composed of figures C, a, n, and d, substantially as shown.
5. The design for carpets, consisting of the figure B, substantially as shown.
6. The design for carpets, consisting of the figure E, substantially as shown.
7. The design for carpets, consisting of the figure O, substantially as shown.
8. The design for carpets, consisting of the figure K, substantially as shown.
9. The design for carpets, consisting of the figure J, substantially as shown.
10. The design for carpets, consisting of the group H, containing figures C and n and figures B, E, K, O, and J, substantially as shown.

CHARLES CHAMBELLAN.
